UNITED STATES PATENT OFFICE.

OSCAR J. ALLERTON, OF CHICAGO, ILLINOIS, ASSIGNOR TO THE FLORSHEIM SHOE COMPANY, OF CHICAGO, ILLINOIS, A CORPORATION OF ILLINOIS.

APPARATUS FOR COATING ARTICLES.

Application filed December 14, 1925. Serial No. 75,247.

My invention relates to apparatus for coating articles, and consists of mechanism which carries the article to be coated to the place of coating where it is sprayed and later 5 dried during a single operation.

The object of my invention is to provide an apparatus for coating articles by a spraying method, transferring them to a point where they are dried during travel, and then 10 depositing them in a bin or hopper during the course of one operation. The apparatus herein disclosed is primarily intended to coat with glue, heels, bases, etc., used in the manufacture of shoes, and to then dry the 15 same so that they can be spotted onto the body of the shoe when desired.

A further object of my invention is to provide an apparatus where, by a continuous conveyor belt, the articles to be coated are 20 passed first under a spraying apparatus where they are covered with the material with which they are to be coated, then continuing to convey them through an efficient drying chamber, and finally depositing them 25 in a bin.

A still further object of my invention is to provide a means for keeping the conveyor belt clean so that all the surplus coating material is removed therefrom before it is 30 turned to the point where uncoated articles are again placed thereon.

Other objects and many of the attendant advantages of the invention will be apparent from the following detailed description, 35 taken in connection with the accompanying drawings in which:

Fig. 1 is a side view of my improved apparatus for coating articles,

Fig. 2 is a plan view of the same,

Fig. 3 is an enlarged plan view of one end 40 of my improved apparatus with some of the parts removed to show the driving mechanism for the several elements required to be driven in the operation thereof.

Fig. 4 is a vertical sectional view on the lines 4-4 of Fig. 1,

Fig. 5 is a like view taken on the lines 5-5 of Fig. 1, and

Fig. 6 is a detailed view of the drying 50 rolls and the adjusting mechanism for the conveyor belt.

Like symbols of reference herein indicate like parts in each of the figures of the drawing.

As illustrated in the drawings and particularly in Fig. 1, my improved apparatus for coating articles has its various parts mounted on the frame 11 which is built up primarily of angle bars. For the purpose of better describing the apparatus shown, we 55 will assume that the same is to be used for the purpose of coating heels for shoes with a coating of glue. After coating, it is necessary to dry the same before they are taken from the apparatus, so that they can be carried to the place where they are spotted onto the body of the shoe, at which time the glue 60 attached thereto in a dried condition is moistened, so that when spotted, they take immediate hold upon the shoe body at the point 65 desired. For the purpose of illustration, let us consider that the table 12 at the front of the machine built on any suitable frame 70 work 13, is adapted by its forward end 14 to extend slightly above the conveyor belt 16. 75 This belt passes around the roll 17 and onto the table 18 supported on the frame 11 around the roller 19 at the rear of the machine, thence around the roller 21 and the adjustable roller 22. From the adjustable 80 roller 22, it passes to the adjustable roller 23, thence upwardly to the roller 24 and back to the roller 17. The belt is continuous in its movement and is operated very slowly, 85 so as to permit the proper coating of the heels with fish glue and thoroughly drying the heel before it drops from the belt. This low speed is accomplished by means of the motor 26 which has a small gear 27 on the shaft thereof, and this gear meshes with a 90 large gear 28 which passes into a reducing mechanism 29. The reduction between the gears 27 and 28 is probably on the ratio of 30 to 1, while the reduction in the reducing mechanism 29 is on the ratio of 50 to 1. The 95 shaft 31 extends from the reducing mechanism 29 under and through the frame 11, and has a sprocket 32 connected at the outer end thereof. This sprocket is provided with a sprocket chain 33 which passes over a larger 100 sprocket 34 on the shaft 36 carrying the roller 17 which carries the belt 16. The

shaft 31 is mounted in a suitable bearing 30, affixed to the side of the frame 11 in any suitable manner, and the shaft 36 is likewise mounted in a bearing 35. The sprockets 32 and 34, and the chain 33 are inclosed by the member 40 to prevent anyone coming into contact with the same during the operation thereof.

At a position a short distance from the front of the apparatus is a spraying booth 37, whose frame 38 is built up of angle bars supported on the frame 11 of the apparatus, and the booth proper consists of sheet metal or other material which extends over and forms a cover for a certain portion of the belt 16, as it passes thereunder. At a suitable point on the frame 38 of the spray booth 37 is a spraying apparatus 39 which is pivotally connected to said frame at the point 41, and this spraying device may be of any desired construction, and no invention is contemplated or a claim made as to any novelty contained therein, so that any well known form of spray device, which will effectually spray the articles as they pass thereunder on the conveyor belt, may be used for this purpose.

The spraying apparatus 39, through its pivotal connection 41 with the frame 37, must be adapted to be turned so that the direction of the streams 45 from the valves 46 can be directed upon the articles being coated, at any desired angle. This pivotal movement is necessary, as will later be explained.

On the rear end of the spraying booth 37 is a bracket 42 which is adapted to carry a motor 43, and this motor has a shaft extending into the interior of the said booth, while a fan is located on said shaft in a suitable position to create a suction in the said booth so that the odors from the glue or other coating material may be drawn upward and passed out through the flue 44.

The lower front portion of the spraying booth 37 is provided with an opening 47, through which air is drawn within the same, while the sides of the said booth have longitudinal openings 48 along the side thereof, as later explained.

Beyond the booth 37 is the drying apparatus 49 which consists of a pair of flues 50, each decreasing in cross-sectional area towards its outer end and connected at the forward end with a semi-circular portion 51. This semi-circular portion is somewhat increased in size at one side of the same to provide space for means for heating the air within said flue. While in the present drawing I have shown a series of coiled steam pipes 52, I do not limit myself to any particular means of heating the air within the flue, as electric grids, hot air, steam or other

methods may be used as desired. At the other side of the semi-circular portion 51, and located on the center line of the interior of said portion and without the same, a small motor 52 is located, and this motor has a shaft 53 which extends into the interior of said portion and has affixed to the end of the shaft and in the center of said portion a fan 54 for circulating the air in said drying apparatus 49. By reference to Figure 5, the flues 50 will be seen and the plate 56 extending between and under the same is provided with openings 57 to permit the warmed air from the flues to pass within the chamber 58 formed between the plate 56, and the top of the belt with warm circulating air. These openings 57 are preferably circular in shape, and are in practice about 12 inches between centers. The chamber 58 is free at both ends of the drying apparatus 49 for the admission of air thereto which causes an air change serving as a means of eliminating moisture from the drier.

The roller 19 is located in a housing 59 which is slidably mounted and is adjusted by means of a screw 61, so that the belt may be tightened at any time to take up excessive slack in the same.

At a position immediately under the spray booth 37, and in the lower part of the framework is a water tank 62 which contains a series of circular brushes 63, each mounted on a shaft 64 which is journaled in the housings 66, and said shaft extends beyond the frame 11 of the machine and through the housing 67 and on the end thereof is a bevelled gear 68 which meshes with a bevelled gear 69 on the shaft 71. This shaft 71 is provided with suitable bearings 72 throughout the length of the same for supporting it at a point near where the bevelled gears 69 are applied, and is supported near its front end in the housing 73 and provided at the extreme front end with the large gear 74 which meshes with a small gear 76 on the rear end of the speed reducer 29, but the speed of this small gear 76 is not reduced, so that the said gear travels at the same rate of speed as the driving gear 28 of the reducer. The rollers 21 and 24 are provided with shafts 77 and 78 which are rotatably fixed in the housings 79 and 81 respectively, which said housings are securely fixed to some portion of the frame 11 as required. The rollers 22 and 23 are vertically adjustable through the bearings 82 and 83 which are slidably mounted in the guides 84 and 86, and these bearings are adjustable by means of the adjusting screws 87 and 88, in order that the belt 16 may be submerged in the water in the tank 62 and lowered to get a good contact with the brushes therein. These rollers 22 and 23 extend into the tank 62, and the belt is low-

ered in order to give its undersurface (which will be the upper surface during the coating operation) a good contact with the bristles on the brushes 63 as they wear down.

5 Between the rollers 23 and 24 is a squeezing or wringing device 89 which consists of a pair of slide rails 91 extending between the angle bars 92 and 93 of the frame 11, and in which are mounted the bearings 94 and 96. These bearings are adapted to provide for the shafts 97 and 98 of the rollers 99 and 100, which are rubber-covered, and the distance between the same is regulated by means of the regulating screws 101 and 102, so that the belt 16 will be absolutely free from water after passing through the said rubber covered rolls.

The operation of my improved apparatus for coating articles is as follows:

20 For descriptive purposes, we will presume that the machine is being used for the purpose of placing fish glue in a liquid state on leather heels, and the glue is dried thereon before leaving the apparatus. The table

25 12 contains raw heels and an operator places the heels in rows such as is shown in Fig. 3, and designated by the numeral 103 upon the belt in close relation to each other, the belt moving in the direction shown in the arrow A. The spraying device 39 can be set so that the jets 45 therefrom can strike the heels at any desired angle by means of moving the bars 104 on the pivotal point 41 to any desired position. As the heels pass

30 the jets of liquid fish glue, they are covered on their upper face, i. e., the face which is later to be connected to the shoe body, with a thorough coating of the glue. They then continue along through the opening 47 into

40 the spray booth 37. As the fan 43 in said booth is being rotated by means of the motor 105, a suction will be created in the booth

which will draw air from the atmosphere through the opening 47 and through the longitudinal holes 48 near the lower edge of the

45 same, and will pass the fumes into the flue 44 where they may be exhausted into the atmosphere, or consumed. The slots or openings 47 in the side of the booth not only prevent glue or coating material from adhering to the side of the booth, but prevent the suction caused by the fan from turning or agitating the articles out of position. This is a very important feature in that the excessive

50 glue has naturally fallen onto the belt around the articles and if they are agitated so that their under surfaces come in contact with the glue on the belt, they will, after passing through the drying process be firmly glued to the belt and will not leave the same at the desired point. A considerable portion of the excess glue will also be caught by the suction and will be deposited in the flue from which it can be removed in the

55 form of powder.

From beneath the booth 37 the heels continue along on the belt 16 and enter the chamber 58 beneath the drying apparatus 49. The fan 54 operated by the motor 52 being at all times in operation, and heat being supplied through the heating apparatus 52, the fan will drive the warm air which it takes from the open end of the chamber 58 down the leg or flue 50, and as the cross sectional area of the said flue decreases in size throughout its length, there will be a tendency to "back-up" or restrict this warm air so that it will pass down through the openings 57 in the bottom plate 56 of said flue and be driven over to the opposite leg 50' where it will enter through the openings 57 and be drawn forward by means of the fan 54 operated therein. It will thus be seen that a constant current of warmed air will be kept circulating from the flue 50 to the flue 50' through the chamber 58, so that the glue on said heels, by the time said heels reach the rear end of said flues, is perfectly dried and the heels then drop off the belt 90 into a container of any kind provided to receive the same and not here shown. The belt then continues over the roller 59 and to the roller 21 and passes downward over the roller 22 into the water filled tank 62.

During the time that the belt is submerged in the water of the tank 62 it is thoroughly brushed and cleansed of all excess glue which has fallen thereon when passing the spraying device 39, and when it reaches the roll 23, it is entirely cleansed, and it then passes upwardly through the rubber covered rolls 99 and 100 where it is squeezed by said rolls and all water removed therefrom, after which said belt then passes around the roll 17 where it is ready to receive a new charge 100 of heels.

It will readily be seen that with this continuous type of conveying belt and with the automatic control of the spraying and drying of the articles on said belt a vast amount of glue coated heels or other coated articles may be finished in a very short space of time and with great uniformity of coating and drying.

It will also be seen that with the combination of gears for operating the brushes 63 in the tank 62, they will be rotated in a direction opposite to the direction of the travel of the belt 16, so that when a series of these brushes are used, the belt will be thoroughly cleansed during its course through the tank, and when it has passed through the squeezing or wringing device 89 and has rounded the roller 17 it will be perfectly clean to receive the row of heels which will therefore be prevented from sticking to the same. This is a particular feature in connection with this machine, in that, if glue in its moistened condition was left upon the belt 120 when it received the heels 103, the lower 125

sides would adhere thereto and the glue would be dried when they pass through the drying apparatus 49, and when they came to the roller 19 they would be prevented from leaving the belt by reason of their adherence thereto.

It is evident that the belt 16, by the reduction gears which have been shown and described, and also by the speed reducer 29, which has been placed between the motor 26 and operating parts, travels at an extremely low rate of speed, which gives the articles placed thereon sufficient time to be sufficiently sprayed when passing under the spraying device 4, and to be sufficiently dried when passing under the drying apparatus.

It is believed that my invention, its mode of operation and many of its inherent advantages, will be understood from the foregoing without further description, and it should be manifest that the details illustrated and described may be varied within wide limits so that I do not limit myself to the exact construction shown and described, but claim as my invention all devices which may fall within the spirit of the matter shown and described and particularly pointed out in the appended claims.

I claim:

1. An apparatus for coating articles, comprising a continuous conveyor belt for carrying articles to be coated, a spraying device for coating said articles, means for drying said coated articles, and a series of brushes rotating contrary to the direction of travel of said belt to remove the superfluous coating material from said belt.

2. An apparatus for coating articles, comprising a continuous conveyor belt for carrying articles to be coated, a spraying device for coating said articles, a spray booth for removing the odor of the coating material, means for drying said coated articles, and a series of brushes rotating contrary to the direction of travel of said belt to remove the superfluous coating material from said belt.

3. An apparatus for coating articles, comprising a continuous conveyor belt for carrying articles to be coated, a spraying device for coating said articles, means for drying said coated articles, a series of brushes rotating contrary to the direction of travel of said belt to remove the superfluous coating material from said belt, and means for removing the water from said belt after said cleansing operation.

4. An apparatus for coating articles, comprising a continuous conveyor belt for carrying articles to be coated, a spraying device for coating said articles, means extending over a portion of the belt, suction means within said last named means for removing the odors of the coating material, means for drying said coated articles, a tank containing water through which said belt passes, brushes in said tank for acting upon said belt during its passage through said tank, and means for removing the water from said belt after its passage through said tank.

5. An apparatus for coating articles, comprising a continuous conveyor belt for carrying articles to be coated, a spraying device for coating said articles, means for drying said coated articles, a series of brushes rotating contrary to the direction of travel of said belt to remove the superfluous coating material from said belt, and rubber covered rolls for removing the water from said belt after said cleansing operation.

6. An apparatus for coating articles, comprising a continuous conveyor belt for carrying articles to be coated, a spraying device for coating said articles, means extending over a portion of the belt, suction means within said last named means for removing the odors of the coating material, means for drying said coated articles, a tank containing water through which said belt passes, brushes in said tank for acting upon said belt during its passage through said tank, and rubber covered rolls for removing the water from said belt after its passage through said tank.

7. An apparatus for coating articles, comprising a continuous conveyor belt for carrying articles to be coated, a spraying device for coating said articles, a booth containing suction means for removing the odors of the coating material, and horizontal openings in said booth to prevent the suction for agitating the articles on said belt.

8. An apparatus for coating articles, comprising a continuous conveyor belt for carrying articles to be coated, a spraying device for coating said articles, means for drying said coated articles, means for cleansing said belt of all superfluous coating material, and a pair of adjustably mounted rubber covered rolls for removing the water from said belt after said cleansing operation.

In witness of the foregoing I affix my signature.

OSCAR J. ALLERTON.
